UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

FOLDER FOR SEWING-MACHINES.

1,180,419.

Specification of Letters Patent. Patented Apr. 25, 1916.

Application filed July 14, 1910. Serial No. 571,976.

To all whom it may concern:

Be it known that I, LANSING ONDERDONK, a citizen of the United States, residing at New York, in the county of New York, 5 State of New York, have invented certain new and useful Improvements in Folders for Sewing-Machines, of which the following is a description, reference being had to the accompanying drawing and to the letters and figures of reference marked thereon.

The invention relates to new and useful improvements in folders for sewing machines, and more especially folders which are adapted to fold a strip of fabric and 15 invert the same as it is led to the stitching mechanism.

An object of the invention is to provide a folder which is especially adapted for folding extremely wide strips of fabric and 20 for guiding the same evenly and smoothly to the stitching mechanism.

The invention consists in the parts, arrangements and improvements hereinafter described and set forth in the appended 25 claims.

In the drawings,—Figure 1 is a plan view of a portion of a sewing machine with my improved folder attached thereto; Fig. 2 is 30 a front view of the folder showing the fabric therein; Fig. 3 is a similar view with the fabric removed; Fig. 4 is a view of the delivery end of the folder; Fig. 5 is a view of the receiving end of the folder; Fig. 6 is 35 a rear view of the folder, showing in dotted lines the edge guide adjusted; Fig. 7 is a horizontal sectional view showing the guide in adjusted position.

In Fig. 1 of the drawings I have shown a portion of the sewing machine which consists of a work support 1, presser foot 2, 40 needles 3, 3, and an upper feeding mechanism 4. These parts are of the usual construction.

My improved folder 5 consists of two 45 U-shaped guiding walls 6 and 7, one of which is located within the other and the outer ends of said walls are joined as at 8 and 9. This forms a closed U-shaped pas-

sage, through which the strip of fabric being folded is adapted to pass. 50

At its delivery end, the folder, as clearly shown in Figs. 1 and 7, is cut at an acute angle to the longitudinal axis of the folder, as indicated at 10. This folder is of the usual type, as above described, and is adapted to be attached to the work support by a shank 11, which is provided with slots 12 receiving screws 13. The shank 11, as clearly shown in Fig. 5, is rigidly attached to a cross brace 14 fastened to the inner 60 guiding walls.

An opening 15 is formed in the outer guiding wall, as shown in Figs. 2 and 3, so as to facilitate the insertion of the fabric into the folder. The folder is attached to 65 the sewing machine so that its longitudinal axis is substantially at right angles to the line of feed, and the strip of material passing through the folder is inverted in a well known manner and led in a direction from 70 the folder substantially at right angles to its longitudinal axis.

Guiding fingers 16, 16, are secured at the outer ends of the U-shaped passage of the folder, and form a guiding surface over 75 which the edge of the fabric turns as it is inverted.

As above noted, my improved folder is especially adapted for folding and directing extremely wide strips of fabric. In order 80 to guide and direct the fold in the strip of fabric, I have provided a guide 17, which, as clearly shown in Fig. 6, is also U-shaped in construction. This guide 17 is rigidly attached to a U-shaped shank 18 (see Figs. 85 5 and 7), which U-shaped shank rests against the inner face of the U-shaped member 17. A spring 19 carried by the bracket 14 bears against the shank 18, and holds it firmly in contact with the inner guiding 90 wall 7. In order to hold the guide 17 in its adjusted position, I have provided a rod 20, which is rigidly attached to the guide 17, see Fig. 6. Said rod is slotted at 21, and a screw 22 passing through the slot is 95 threaded into the bracket 14 and serves to

hold the guide 17 in adjusted position. On the outer end of the rod 20 is a cross bar 23, which passes through a collar 24 formed in the rod 20, and is secured therein by a set screw 25.

The fabric is led from the supply over the cross bar 23, as shown in Fig. 1, and thence to the U-shaped passage of the folder. After passing through the folder the fabric 10 is led in a direction at right angles thereto, the edges of the fabric being guided by the fingers 16 and the folded portion of the fabric being directed by the guide 17. When it is desired to fold a narrower strip of 15 fabric, the set screw 22 is released, and the guide 17 adjusted, as shown in dotted lines in Figs. 6 and 7. The U-shaped shank portion 18 will form an extension of the inner guiding wall, and support the fabric until 20 it is inverted and led to the stitching mechanism.

Having thus described my invention, what I claim as new and desire to secure by Letters Patent, is:—

- 25 1. A folder comprising spaced U-shaped guiding walls having the delivery end thereof arranged at an acute angle to the longitudinal axis of the folder, a U-shaped guide mounted on said folder and extending in a direction substantially at right angles to the longitudinal axis of the folder, said guide being located at the delivery end of the folder for guiding the fold in said strip, means for adjusting said guide longitudinally of the folder, said guide having a U-shaped shank conforming in curvature to the inner guiding wall, whereby when said guide is adjusted, said shank forms an extension of the inner guiding wall, and a spring for holding said shank in close contact with the inner guiding wall.
- 30 2. The combination of stitch-forming mechanism including a needle, a folder comprising spaced U-shaped guiding walls, means for supporting said folder with its longitudinal axis substantially at right angles to the direction of stitching, the delivery end of said folder being arranged at an acute angle to the longitudinal axis of the folder, whereby the strip guided by the folder may be inverted, a guide carried by said folder for directing the folded portion of the strip, said guide being curved to conform to the fold in the strip and extending to a point substantially in a line at right angles to the line of feed and containing the needle, and means for adjusting said guide in a direction longitudinal of the folder.
- 35 3. The combination of stitch-forming mechanism including a needle, a folder comprising spaced U-shaped guiding walls, means for supporting said folder with its longitudinal axis substantially at right

angles to the direction of stitching, the delivery end of said folder being arranged at 65 an acute angle to the longitudinal axis of the folder, whereby the strip guided by the folder may be inverted, a guide carried by said folder for directing the folded portion of the strip, said guide extending to a 70 point substantially in a line at right angles to the line of feed and containing the needle, said guide having a U-shaped shank forming a curvature with the inner guiding wall, whereby when said guide is adjusted, said 75 curved shank forms an extension of the inner wall.

4. The combination of stitch-forming mechanism including a needle, a folder comprising spaced U-shaped guiding walls, 80 means for supporting said folder with its longitudinal axis substantially at right angles to the direction of stitching, the delivery end of said folder being arranged at an acute angle to the longitudinal axis of the folder, whereby the strip guided by the folder may be inverted, a guide carried by said folder for directing the folded portion of the strip, said guide extending to a point substantially in a line at right angles to the 85 line of feed and containing the needle, said guide having a U-shaped shank forming a curvature with the inner guiding wall, whereby when said guide is adjusted, said curved shank forms an extension of the inner 90 wall, a bar attached to said guide, and means for securing said bar in adjusted position.

5. A folder for sewing machines including in combination, spaced U-shaped guiding walls, a bracket secured to the inner wall, a 100 shank secured to said bracket, means for adjustably attaching said shank to the bed plate of the machine, whereby said U-shaped guiding walls extend above and below said bed plate, the delivery end of said folder 105 being arranged at an acute angle to the longitudinal axis, whereby a strip led through said folder may be inverted.

6. A folder for sewing machines including in combination, spaced U-shaped guiding 110 walls, a bracket secured to the inner wall, a shank secured to said bracket, means for adjustably attaching said shank to the bed plate of the machine, whereby said U-shaped guiding walls extend above and below said bed plate, the delivery end of said folder being arranged at an acute angle to the longitudinal axis, whereby a strip led through said folder may be inverted, an adjustable guide carried by the folder for 115 guiding the folded portion of the strip after it is inverted.

7. The combination of a U-shaped folder having its delivery end arranged at an acute angle to the longitudinal axis thereof, a rod 120 adjustably attached to the folder, and a 125

cross bar carried by said rod and extending in a vertical direction for guiding the strip to the folder.

8. The combination of a U-shaped folder having its delivery end arranged at an acute angle to the longitudinal axis thereof, a rod adjustably attached to the folder, and a cross bar carried by said rod and extending in a vertical direction for guiding the strip

to the folder, and a guide carried by said folder at the delivery end thereof for guiding the strip after it is inverted.

In testimony whereof I affix my signature, in presence of two witnesses.
